No. 658,582.

W. M. POTTER.

Patented Sept. 25, 1900.

SAND PRESS.

(Application filed May 21, 1900.)

(No Model.)

UNITED STATES PATENT OFFICE.

WILLIAM M. POTTER, OF SYRACUSE, NEW YORK, ASSIGNOR TO E. C. STEARNS & CO., OF SAME PLACE.

SAND-PRESS.

SPECIFICATION forming part of Letters Patent No. 658,582, dated September 25, 1900.

Application filed May 21, 1900. Serial No. 17,435. (No model.)

To all whom it may concern:

Be it known that I, WILLIAM M. POTTER, of Syracuse, in the county of Onondaga, in the State of New York, have invented new and useful Improvements in Sand - Presses, of which the following, taken in connection with the accompanying drawings, is a full, clear, and exact description.

My invention relates to sand-presses for forming molds used in foundries; and it consists in a special construction of press embodying certain new features by which the machine is simplified, the cost reduced, and the operation improved.

15 My invention is fully illustrated in the accompanying drawings, in which—

Figure I is an isometric view of my press with the movable parts in the second position. Fig. II is an end elevation thereof, showing the parts in the first position; Fig. III, a corresponding elevation in the third position. Fig. IV is an enlarged inner elevation of a portion of the press, portions being shown in dotted lines and portions in section, 25 taken on line IV IV of Fig. I. Figs. V and VI are respectively front and side elevations of one end piece and upright-carrying presser-head detached. Fig. VII is an end elevation of table bed and bars detached. 30 Fig. VIII is an elevation of shaft and connected parts. Fig. IX is a front elevation of one leg detached, showing the integral lug on its outer face and the washer fitted to the lug.

The table for the press is composed of the 35 legs 1 1, provided with enlarged feet 2 2 and flattened tops 3 3, to which is fitted the table-bed 4, of inverted-V shape, provided with flanges 5 5 for securing bolts. On the table-bed and arranged at right angles thereto are 40 the table-bars 6 6 for supporting the flask, on which may be arranged an adjustable gage 7 for fixing the position of the flask. The legs are provided on their outer faces with lugs 8, carrying washers 9, fitting slots 25 in 45 the end piece and acting as guides therefor.

In the ends of the table-bed is journaled the shaft 13, having at each end the head 14 and an integral crank 15 and at one end the socket 16, provided with set-screws 17 for the 50 operative lever 18. To the cranks, by the draw-bars 21 21, are connected the end pieces

22 22, having the integral arms 23 23 on their lower ends for attachment of springs, extending inwardly through the leg-openings 24 24, which act as a guide therefor, the arm 23 following the curve on the left of this opening, as shown in Figs. II and III. In the lower ends of the end pieces are the guide-slots 25 25, fitting the lugs 8 8. The end pieces are also provided with outer flanges 26 26 and 55 corresponding inner guide-flanges 27 27, engaging with the antifriction-rollers 29 29, secured on the table ends or on other fixed part. The end pieces are also formed with integral ears 30 30 for the attachment of the draw-bars and sockets 31 31 for the uprights 32 32, which are threaded to carry adjustably the presser-head 33, nuts 34 34 being provided for holding in position and permitting vertical adjustment of the presser-head. 70

Springs 40 40 are connected to the arms 23 on the end pieces and to some suitable fixed point on the frame, as lugs 41 41, to act as a counterbalance and draw the presser-head back out of the way when the mold is completed and the pull on the lever is released. 75

My machine is operated as follows: Beginning with the parts in position shown in Fig. II, the flask is set in place on the table, containing the mold and sufficient sand. The 80 presser-head is then adjusted up or down on the uprights to bring it low enough to exert sufficient pressure. The operator, standing in front of the press, draws the lever forward to the position of Fig. I, bringing the presser-bar directly over the flask. He then continues to draw the lever forward and down to the position in Fig. III, by which the presser-head is forced directly down upon the sand, exerting sufficient regular pressure thereon 85 to make a perfect compact mold. The lugs and antifriction-rollers on the outer face of the legs coöperate with the slot and flanges to act as guides. When the mold has thus been pressed, the lever is released and the 90 presser-head returned to its first position by the springs. 95

Having thus fully described my invention, what I claim, and desire to secure by Letters Patent, is—

1. In combination in a sand-press, supporting-legs, guide-lugs on the outer faces of the

- legs, a table-bed fitted and secured thereto, a cross-shaft journaled therein under and parallel to the bed, cranks on the ends of the shaft, an operating-lever on one end, end pieces provided with slots to fit the guide-lugs on the legs and with flanges on the inner face of each, draw-bars connecting the upper ends of the end pieces to the cranks, threaded uprights on the end pieces, a presser-head 5 adjustably supported thereon, and an anti-friction-roller secured on the outer face of the table-bed engaging with flanges on the inner faces of the end pieces when the latter are turned in a vertical position.
15. 2. In combination in a sand-press, supporting-legs, guide-lugs on their outer faces, a suitable table-bed fitted and secured thereto, a cross-shaft journaled therein under and parallel to the bed, cranks on the ends of the shaft, an operating-lever on one end, end pieces provided with slots to fit the guide-lugs, draw-bars connecting the upper ends of the end pieces to the cranks, threaded uprights on the end pieces, a presser-head adjustably supported thereon, integral arms on the lower ends of the end pieces inwardly extending through openings in the legs and springs connecting said arms to the frame.
3. In combination in a sand-press, suitable legs, a table-bed secured to the top thereof, integral table-bars on the bed, integral guide-lugs on the outer faces of the legs, antifriction-rollers on the outer surface of frame, washers fitted to the guide-lugs, a cross-shaft 35 journaled under and parallel to the table-bed having integral cranks, and an operating-lever fitted to one end of the shaft, end pieces having slotted lower ends to fit the guide-lugs, integral flanges on the inner faces of the end pieces to engage with antifriction-rollers on the outer faces of the frame, threaded uprights on the end pieces, a presser-head adjustably carried on the uprights, integral arms 40 on the lower ends of the end pieces inwardly extending through openings in the legs on each side and spiral springs connected to the arms and to the frame.
4. In combination in a sand-press, suitable supporting-legs having enlarged bases, openings and flattened tops, a table-bed of inverted-V shape having end plates fitted thereto and secured to the top of said legs, integral cross-bars on said table-bed, an adjustable gage fitted to said cross-bars, integral guide-lugs on the outer faces of the table-legs, 45 antifriction-rollers on the outer faces of said end plates, a shaft journaled in said end plates under and parallel to the table-bed, integral heads and cranks on the ends of the shaft, an integral, cylindrical socket provided with a set-screw on one end thereof, a lever fitted to the socket, corresponding end pieces fitted to the outer faces of the legs having integral ears on the upper ends, slotted lower ends to fit the guide-lugs, outer flanges, inner guide-lugs to engage with the antifriction-rollers when the end pieces are turned into their vertical position, draw-bars journaled to said cranks and to integral ears on the upper ends of the end pieces, threaded uprights secured to the upper end of the end pieces, a presser-head carried on the uprights, nuts fitted thereto for adjusting the position of the presser-head, integral arms on the lower ends of the end pieces inwardly extending through openings in the legs and spiral springs attached to said arms and to fixed studs on the inner faces of the legs to return the presser-head into first position when the operation has been completed.
- In testimony whereof I have hereunto signed my name.
- WILLIAM M. POTTER. [L. S.]
